UNITED STATES PATENT OFFICE.

WILLIAM GREGG, OF PHILADELPHIA, PENNSYLVANIA.

IMPROVED REFRIGERATOR.

Specification forming part of Letters Patent No. 36,346, dated September 2, 1862.

To all whom it may concern:

Be it known that I, WILLIAM GREGG, of the city of Philadelphia, in the State of Pennsylvania, have invented a new and useful Improvement in Refrigerators; and I do hereby declare that the following is a full, clear, and exact description of the construction and operation of the same, reference being had to the accompanying drawings, making a part of this specification, in which—

Figure 1 is a vertical central section, and Fig. 2 a plan view, of the said improvement applied.

Like letters indicate the same parts when in the different figures.

The object of my invention is the production of a more economical refrigerator for domestic use; and it consists in combining with a refrigerator a common water-cooler in the peculiar manner hereinafter described, so that the usual quantity of ice hitherto required for either will be fully adequate to the requirements of both, and the water-cooler be outside of the refrigerator.

In the drawings, A is the refrigerator, B the water-cooler, and C the ice box connecting them both together.

The refrigerator A may be made in any of the usual forms, and with hinged shelves a' a' or other devices for holding provisions; but instead of placing the ice box C in the top or at one side, as heretofore, I fix it permanently in the middle of the bottom of the refrigerator, so that its lower end shall project through the same, say, about three inches, the said ice box being provided with a drip-hole, c', in its bottom and with a close lid, c", at its top, substantially as represented in the drawings. In Fig. 2 the lids of both the refrigerator and the ice box are removed and the shelves a' a' raised up.

The body of the water-cooler B may also be made in any of the common forms; but instead of the usual cover or lid the projecting portion of the bottom of the ice box C is adapted to serve the purpose, the water-cooler B being fixed in an upright position upon a bench or plank, D, so as to serve as a supporting-column for the refrigerator, as seen in Fig. 1. It will therefore be seen that in this invention the refrigerator A, in connection with its ice box C, being made to serve together as a cover for the water-cooler B, it is to be lifted off in replenishing the cooler with water or for introducing a portion of the ice where expedition may be required.

In operation it will be seen that the ice in the box C will serve the double purpose of cooling the refrigerator and imparting additional coolness to the water as it melts and drips through the hole c' into the cooler below it, and at the same time the cooler B retards the melting of the ice, and that, therefore, economy in regard to the quantity of ice heretofore required for both purposes will be afforded without diminishing the capacity of the refrigerator for the reception of provisions.

Having thus fully described my improvement and pointed out its utility, what I claim as new therein, and desire to secure by Letters Patent, is—

Combining a water-cooler with a refrigerator so that the latter, in connection with its ice box, shall form the cover of the water-cooler, the whole being arranged together so as to operate in the manner described, for the purposes specified.

WILLIAM GREGG.
